CLAIM

The ornamental design for a protective cover for rolls of toilet paper, as shown.

DESCRIPTION

FIG. 1 is a side elevational view of a protective cover for rolls of toilet paper showing my new design;

FIG. 2 is a rear elevational view;

FIG. 3 is a top plan view;

FIG. 4 is a bottom plan view;

FIG. 5 is a side elevational view, with the cover in the raised position;

FIG. 6 is a perspective view; and

FIG. 7 is a front elevational view.
